FIG. 3

Inventor:
Walter C. Fellows.
By *Walter C. Fellows*
Attorney.

UNITED STATES PATENT OFFICE.

WALTER C. FELLOWS, OF PHILADELPHIA, PENNSYLVANIA, ASSIGNOR TO C. R. CARVER COMPANY, A CORPORATION OF PENNSYLVANIA.

HAND PROTECTOR FOR PRESSES.

Application filed October 2, 1926. Serial No. 139,122.

The object of my invention is to provide an efficient finger guard for stamping or embossing presses and for other machines in which there is employed a reciprocable moving part in the path of the fingers of the operator during the feeding of the paper or material required to be acted upon.

My object is further to provide a finger protector for machines known as stamping and embossing presses in which a vertically reciprocating plunger cooperates with a die and between which the sheets or cards are inserted and removed by hand, the protector being supported by the main frame or housing and adapted to swing in forward and backward directions immediately above the die and below the plunger, but at all times under the control of and in timed relation with the said plunger.

My invention has a further object in that the finger guard is automatically moved backward substantially clear of the die, whereby free access may be had thereto and to the counter-block of the plunger when changing them or adjusting the press; and wherein upon the downward movement of the plunger, the finger guard is moved forward immediately above the die and chuck carrying the same, whereby at the moment of danger the finger guard will positively force the fingers clear of the die and plunger so as not to be pinched or crushed thereby.

My object is further to employ cam devices for imparting a greater or less throw to the links and guard to suit dies of different sizes in the press.

With these and other objects in view to be performed and secured, my invention consists of certain improvements in finger guards for stamping and embossing presses and for other machines, having the particular features of novelty as set forth in the following specification and defined in the claims.

Referring to the drawings: Fig. 1 is a side elevation of a stamping press having my improvements applied thereto; Fig. 2 is a similar view (in part) with the operative portions moved to other positions; Fig. 3 is a front view of my improvement largely separated from the press; Fig. 4 is a plan view with the upper portion cut away on line 4-4; and Fig. 5 is a perspective view of one of the operating cams.

The main frame and housing of the press is shown at 2 and in which the vertical plung-

er 3 is guided, the same hung in a cross head 21 and reciprocated by the links 22 in the well known manner. It is immaterial to my invention as to the special use of the press or machine and also as to the special features of construction employed. The plunger 3 is fitted with a counter-block 4 detachably secured to the lower end thereof. 5 is a die carried by the chuck 6, adapted to be reciprocated backward and forward 65 over the bed 7 of the machine, in the usual manner.

12 is the finger guard and is swung backward and forward between the die 5 and plunger 3 by means to be now described. 8 70 is a bracket extending across the front and sides of the housing 2 in which the plunger is guided, said bracket being secured in place by cap screws 2^a or otherwise. Hinged at 10, 10, upon the opposite sides of the bracket 8 are the vertical links 9, 9, whose lower ends are hinged to opposite sides of the finger guard 11 at 12, 12, said latter hinge points being also at the lower part of the guard when in ejecting position (Fig. 1). Similarly, hinged at 15, 15, on opposite sides of the bracket 8 are the vertical links 13, 13, whose lower ends cross the links 9, 9, and are respectively hinged to opposite sides of the finger guard 11 at 14, 14, said latter hinge 85 points being at the upper part of the guard when in ejecting position. Where these two sets of links 9 and 13 cross each other in pairs, scissor-like, I provide guard plates 13^a secured to the links 13 and extending backward over the links 9, to prevent the fingers accidentally getting between said links at a time when the finger guard 11 is moved farthest to the rear (Fig. 2). The links 9 and 13 together with the finger guard 11 form 95 a toggle arrangement, which as a whole is yieldingly forced rearward by springs 20. To move the links and guard forward in the opposite direction, the following instrumentalities are employed. The upper ends of the 100 links 13, 13, constituting their pivotal or fulcrumed portions are provided with short arm portions having pivoted rollers 16, 16, which rest against the cam faces 17 of cam blocks 17^a, 17^a, the said blocks secured in operative positions upon vertical operating rods 18, 18, whose upper ends are secured to and moved by the cross head 21 in an up and down direction with the plunger 3. The lower ends of the rods 18, 18, are guided 105

110

through apertures in side lugs 8^a, 8^a, of the bracket 8, for steadyng the rods while the cams 17^a are in operation during the shifting of the finger guard 11. The cams are 5 quick acting by reason of the abrupt cam shoulders 17 which are designed to quickly throw the guard 11 from its rear position (Fig. 2) to a forward position somewhat beyond that shown in Fig. 1, the cam being 10 shown in action with the parts as illustrated in said Fig. 1. The action of the two cams 17^a is constantly opposed by the springs 20, so that the springs insure that the rollers 16 shall be constantly in operative contact 15 with the cam surfaces 17. The springs 20 are connected at one end with the links 13 and at the other end with the press housing 2. 16

When the finger guard 11 is moved to the 20 most rearward position (Fig. 2), the die 5 and counter-block 4 are fully exposed for replacement when necessary, and the space between the die and plunger is a maximum for free introduction and removal of the 25 paper or card sheets in the periods between the stamping or embossing operations.

In my preferred construction, I provide the cam with cam surfaces 17 on opposite sides and of different "throws", so that either 30 cam surface may be adjusted to operative position, to cause the links and guard bar to be moved a greater or less distance to suit dies and counter-blocks of different sizes. Thus, if the die of one size required the 35 action of one of the cam surfaces 17 to move the guard 11 to the proper distance forward and backward, then when the die and counter-block are changed to a larger size, the "throw" of the links and guard must be given 40 a greater movement and consequently the other cam surface 17 having a greater "throw" must be brought into operative position. The construction employed for securing these results consists of the following 45 features. The rods 18 are round and the cam blocks 17^a are free to be rotated upon said rods to bring either of the cam surfaces 17, 17, into operative position. To insure exact 50 positioning with one hundred and eighty degree adjustments of the cam blocks, the rods 18 are provided with cross pins 23 to be received in diametric grooves 24 on the upper ends of the cam blocks and said relation held 55 by the action of coil springs 19, carried on the rods and pressing the cam blocks upward against the pins. When the adjustments are 60 made, the set screws 25 are tightened for securing the cams rigidly to the rods. These features are best shown in Fig. 5. It will 65 be understood that, if desired, only one set of links 9 and 13 and one cam block therefor need be used, but in view of the greater strength and nicety of the hinge joints required, I prefer to employ two sets of links 66 and cam blocks as shown.

If it should be desired to turn the finger guard forward and upward for providing free access for any cause, this may readily be done by disconnecting the springs 20 and moving the links 9 and 13 forward and upward about their hinge points 10 and 15. 70

It will now be apparent that I have devised a novel and useful construction which embodies the features of advantage enumerated as desirable, and while I have in the present 75 instance shown and described the preferred embodiment thereof which has been found in practice to give satisfactory and reliable results, it is to be understood that I do not restrict myself to the details, as the same are 80 susceptible of modification in various particulars without departing from the spirit or scope of the invention.

Having now described my invention, what I claim and desire to secure by Letters Patent is:

1. A machine having a fixed frame and two operative parts which have a relative reciprocatory movement, in combination with means to guard the fingers of the operator 90 comprising a transverse finger guard, crossing links hinged at their upper ends to the fixed frame and at their lower ends to the finger guard and arranged to swing the same backward and forward between the two operative parts of the machine and rotated upon a transverse axis into a vertical position during its forward movement, means yieldingly acting upon the links to cause the finger guard to be moved to the rear of the said operative parts, and mechanically operating means actuated by moving parts of the machine in timed relation with the relative movements of the operative parts thereof for moving the links and finger guard forward of the said operative parts in opposition to the yielding operation of the means aforesaid. 95

2. The invention according to claim 1, wherein further, the means yieldingly acting upon the links comprise a spring and the mechanically operating means consists of cam devices movable by the same means which provides the relative reciprocatory movement between the two operative parts of the machine, said spring and cam devices operating upon one of the links only. 110

3. The invention according to claim 1, wherein further, the two operative parts comprise a die and a plunger of a press with means to reciprocate the plunger, the yieldingly acting means consist of spring devices, and the mechanically operating means is operated by connections with the means for reciprocating the plunger and wherein also the connected crossing links and finger guard 120 are operated in unison. 125

4. The invention according to claim 1, wherein further, the mechanically operating means consists of reciprocating cam mechanism acting upon the connected crossing links 130

whereby they are given a swinging movement in timed relation with the relative reciprocatory movements of the two operative parts of the machine.

5. A press having a die and reciprocating plunger, combined with a finger guard therefor consisting of a guard bar adapted to be moved between the die and plunger, a pair of crossing links having their upper ends hinged 10 to the press structure and their lower ends hinged to the finger guard by which it is suspended so as to swing backward and forward between the die and plunger and rotate upon the lower ends of each of the links, means for 15 causing the links to be moved backward a distance sufficient to move the finger guard from in front to the rear of the die and plunger to permit changing of the die, and means movable in timed relation with the reciprocations 20 of the plunger for causing the guard bar to be moved forward under the plunger and clear of it as it descends to cooperate with the die.

6. The invention according to claim 5, 25 wherein further, the means for causing the links to move backward to the rear of the plunger consists of spring devices, and the means for causing the finger guard to be moved forward in front of the plunger consists of positively acting cam mechanism acting 30 upon one of the crossing links and through it and the finger guard upon the other crossing link and operative from the plunger actuating means.

35. 7. The invention according to claim 5, wherein further, the means for causing the links to move backward to the rear of the plunger consists of spring devices, and the means for causing the finger guard to be 40 moved forward in front of the plunger consists of positively acting cam mechanism acting upon one of the crossing links and through it and the finger guard upon the other crossing link and operative from the 45 plunger actuating means, said mechanism including a vertically reciprocating rod, a cam

secured thereto so as to be movable with it and having a cam shaped side face, and a contact means attached to the first mentioned crossing link resting against the cam face for 50 actuating the link and finger guard carried thereby and while the latter is guided by the other crossing link.

8. The invention according to claim 5, 55 wherein further, the means for causing the links to move backward consists of spring devices, and the means for causing the finger guard to be moved forward consists of positively acting cam mechanism acting upon one of the crossing links and operative from 60 the plunger actuating means, said mechanism including a vertically reciprocating rod having a transverse pin, a cam block sleeved upon the rod and having a diametric groove to receive the transverse pin and to permit the 65 cam block to assume two positions 180° apart, said cam block having cam surfaces along its length and 180° apart, spring devices for holding the cam block against the transverse pin, positive means to clamp the cam block 70 to the rod, and means connected with the link and actuated by the cam surfaces for operating the connected links and finger guard carried thereby.

9. The invention according to claim 5, 75 wherein further, the means for causing the connected crossing links and finger guard to move forward comprises a cam block movable in timed relation to the plunger and having two cam portions of different throws, means 80 for adjusting the cam block to bring either of the two cam portions into operative position, and means actuated by the cam portion which is in operative position for actuating the connected links and finger guard, whereby the finger guard may be moved to a greater or less distance to suit dies and counterblocks 85 of different sizes.

In testimony of which invention, I hereunto set my hand.

WALTER C. FELLOWS.
